TRAP GUN

Vaud L. Wintersteen, Timpani, Colo.

Application June 22, 1944, Serial No. 541,604

6 Claims. (Cl. 43—84)

This invention relates to a trap gun of the toxic gas type designed for eliminating coyotes and other predatory animals. The principal object of the invention is to provide an economical, easily set trap gun which will be more positive and certain in its action than present trap guns.

Trap guns are in use at the present time. Most of these, however, are not 100% efficient due to the fact that the animal need not have his head in the proper position for the kill at the time the trap is sprung. An object of this invention is to provide a trap gun which cannot be fired accidentally and which cannot be fired by the animal until his mouth is directly in line with the line of fire of the gas cartridge so that the discharge thereof will be expelled directly into the animal's mouth.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a vertical section through the improved trap gun illustrating it in the set position;

Fig. 2 is a similar fragmentary section illustrating the gun in the firing position;

Fig. 3 is a side view of the improved trap gun;

Fig. 4 is a cross-section through the head thereof taken on the line 4—4, Fig. 1;

Fig. 5 is a similar cross-section taken on the line 5—5, Fig. 1;

Fig. 6 is a detail view of an anchor plate which may be employed with the gun;

Fig. 7 is a detail section illustrating the firing pin mechanism; and

Fig. 8 is a detail side view of the mechanism housing of the improved trap gun.

The improved trap gun employs a cup-like mechanism housing 10, from the bottom of which a stake 11 projects. This stake is fixedly secured in axial alignment with the housing 10 and terminates in a pointed ground piercing head 12.

The upper extremity of the housing 10 is open and the opening is surrounded by a shoulder having suitable threads 13 for receiving a cap sleeve 14. The cap sleeve is imbedded in a surrounding skirt or shield 15 which may be a part of the sleeve or may be formed of plastic or other

similar material and permanently attached to the sleeve as illustrated.

A standard gas cartridge 16 is received in a cartridge barrel 17 having an open upper extremity and an internally threaded lower extremity. The open upper extremity of the barrel 17 is covered and surrounded by a fabric pad 18 formed from a plurality of layers of cloth secured thereon by means of string or thread ties 19 which are wrapped about the pad 18 and the barrel 17. The lower extremity of the barrel 17 is threaded onto the upper extremity of a firing pin chamber 20 which loosely rests upon a suitable cushion 21 in the bottom of the housing 10.

The firing mechanism is of standard design and can be purchased on the open market. It consists of a plunger 22 against which a compression spring 23 acts. The plunger terminates in a projecting firing pin 24 which can be expelled

through a pin opening 25 into contact with the cap of the cartridge 16. The plunger is normally retained in the retracted position by means of a cam 26 formed on a cam lever 27, as shown more in detail in prior U. S. Patent No. 2,145,488.

In this device, the cam lever 27 extends through a notch 28 in the upper edge of the housing 10, in which it is retained by the sleeve 14.

In use, the fabric pad 18 is saturated with any odoriferous baiting fluid which will attract the animal. The device is set by driving the stake 11 into the ground to a position approximately indicated by the broken ground line G in Fig. 3. During the driving operation, the shield 15 and the cartridge mechanism are removed from the housing. Any suitable driving plug can be placed in the housing for the driving operation.

When the housing is in place, the cartridge 16 is slipped into the barrel 17 and the latter is screwed onto the chamber 20. The chamber 20 with its assembled cartridge 16, barrel 17, and pad 18 are then dropped into the housing 10 with the cam lever 27 in the notch 28. The sleeve and cap 13—15 are then threaded onto the housing and the device is ready for use.

It will be noted that the pad 18 has a rounded upper extremity which projects only slightly above the shield 15. Therefore, the only way that the animal can grip the pad is with his front teeth. This places the animal's mouth directly over the shield with his head in axial alignment with the cartridge 16. There are no projecting portions that he can take in his teeth to fire the gun as in the usual trap gun. When he has gripped the pad in his teeth and drawn upwardly thereon, he will lift the entire firing mechanism as shown

in Fig. 2. This will cause the hinged extremity of the lever 27 to rotate the cam 26 so as to release the plunger 22, allowing the spring 23 to snap the firing pin 24 against the cap of the cartridge, discharging it through the fabric of the pad 18, as illustrated in Fig. 2, into the mouth of the animal.

The skirt of the shield 15 projects outwardly and downwardly about the notch 28 and the lever 27 to prevent accidental contact therewith and to prevent soil, sand and other foreign material from interfering with the operation of the gun.

Should the device be used in sand where it would be difficult for the head 12 to retain it in position, an anchor plate 29, such as illustrated in Fig. 6, is employed. This anchor plate is provided with a central opening 30 for the passage of the stake 11 and with a side channel 31 to allow the stake to enter the central opening. It is placed immediately above the head as illustrated and covered with sand or earth in setting the trap.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A trap gun comprising a cup-like housing; a rod projecting downwardly from said housing; a firing mechanism loosely contained within said housing; a firing lever projecting from said mechanism through a notch in the upper edge of said housing; a cartridge receiving barrel detachably secured to the upper extremity of said mechanism; and a skirt-like shield threaded onto the upper extremity of said housing to retain said lever in its notch.

2. A trap gun comprising a cup-like housing; a rod projecting downwardly from said housing; a firing mechanism loosely contained within said housing; a firing lever projecting from said mechanism through a notch in the upper edge of said housing; a cartridge receiving barrel detachably secured to the upper extremity of said mechanism; a skirt-like shield threaded onto the upper extremity of said housing to retain said lever in its notch; and a flexible pad secured over the upper extremity of said barrel.

3. A trap gun comprising a cup-like housing; a rod projecting downwardly from said housing;

a firing mechanism loosely contained within said housing; a firing lever projecting from said mechanism through a notch in the upper edge of said housing; a cartridge receiving barrel detachably secured to the upper extremity of said mechanism; a skirt-like shield threaded onto the upper extremity of said housing to retain said lever in its notch; and a flexible pad secured over the upper extremity of said barrel, the skirt of said shield being enlarged to extend downwardly about said housing to enclose the projecting extremity of said lever.

4. A trap gun comprising a cup-like housing; a rod projecting downwardly from said housing; a firing mechanism loosely contained within said housing; a firing lever projecting from said mechanism through a notch in the upper edge of said housing; a cartridge receiving barrel detachably secured to the upper extremity of said mechanism; a skirt-like shield threaded onto the upper extremity of said housing to retain said lever in its notch; and a cushion positioned within said housing to support said mechanism therein.

5. A trap gun comprising a cup-like housing; a rod projecting downwardly from said housing; a firing mechanism loosely contained within said housing; a firing lever projecting from said mechanism through a notch in the upper edge of said housing; a cartridge receiving barrel detachably secured to the upper extremity of said mechanism; a skirt-like shield threaded onto the upper extremity of said housing to retain said lever in its notch; and a pointed enlarged head formed on the lower extremity of said stake for retaining it in the ground.

6. A trap gun comprising a cup-like housing; a rod projecting downwardly from said housing; a firing mechanism loosely contained within said housing; a firing lever projecting from said mechanism through a notch in the upper edge of said housing; a cartridge receiving barrel detachably secured to the upper extremity of said mechanism; a skirt-like shield threaded onto the upper extremity of said housing to retain said lever in its notch; a pointed enlarged head formed on the lower extremity of said stake for retaining it in the ground; and a slotted anchor plate detachably engaging said stake above said head to prevent its withdrawal.
